His Attorney.

UNITED STATES PATENT OFFICE

EDWARD WITTCOFF, OF ST. LOUIS, MISSOURI

HAT

Application filed August 13, 1928. Serial No. 299,250.

This invention relates to hats, and has special reference to a hat having a crown comprising pivotally united sections capable of variable adjustments to provide a closed 5 crown or a ventilated crown, as desired.

An object of the invention is to provide a hat wherein the brim and the lower portion of the crown pivotally support a crown top in a relationship in which said top may be 10 adjusted upon and about the lower portion of the crown to provide a closed crown, or may be tilted to provide an opening.

Other objects will appear from the following description, reference being made to 15 the drawing in which

Fig. 1 is a top plan view of my improved hat.

Fig. 2 is a side elevation.

Figs. 3 and 4 are front and rear elevations, 20 respectively.

Fig. 5 is a vertical sectional view on the line 5—5 of Fig. 1.

Fig. 6 is a vertical sectional view on the line 6—6 of Fig. 1.

25 A brim 1 may be provided at the front with a visor of suitable material and color to shade and protect the eyes of the wearer. However, this visor may be omitted, if desired, and the brim may be of usual construction.

30 The brim is in connection with a lower crown section 3 which is open at the top and has its upper edge enclosed by a strip of binding material 4 when such material is 35 needed.

At the front the upper edge of the lower crown section is formed with a notch 5.

40 The upper crown section 6 comprises an approximately circular depending crown wall that telescopes around the upper portion of the lower crown section 3 and is pivotally connected thereto at opposite sides by pivots 7 which may be in the form of open eyelets 45 to permit circulation of air into and from the hat. In case the same is needed, the lower edge of the upper crown section is enclosed by a strip 8 of binding material. The lower edge of the upper crown section may 50 be provided with notches 9 to permit the up-

per crown section to be tilted farther than would otherwise be possible.

The relationship of the upper crown section to the lower crown section is such that when the upper crown section is not tilted a 55 substantially closed crown is formed, as will be understood by reference to Figs. 2, 3 and 4. This is because the wall 6 of the upper crown section telescopes around the upper portion of the lower crown section. When 60 the upper crown section is tilted upwardly and rearwardly, as shown in Fig. 5, a substantial opening is formed at the front of the crown permitting free circulation and 65 passage of air, and such circulation may be increased by the provision of eyelets 10 in the sides of the upper crown section.

From the foregoing it will be apparent that my improved hat is designed and adapted for use in warm weather and functions to 70 promote the circulation of air through the crown of the hat. The size of the opening at the front of the hat may be varied, as desired, the upper crown section being retained in whatever adjustment it is placed by the 75 clamping arrangement of the pivots 7 and the frictional contact of the telescoping surfaces of the crown sections.

The construction and arrangement of the parts may be varied within equivalent limits 80 without departure from the nature and principle of the invention. The hat may be made of woven or felted materials or of any appropriate hat material.

I claim:

1. A hat comprising a brim, and a lower crown section in connection with the brim and having a notch in its upper edge at the front, in combination with an upper crown section telescoping upon the upper portion of 90 said lower crown section and having a notch in its lower edge at the front, and means pivotally connecting said two crown sections together and permitting movement of said upper crown section to position to form a closed 95 crown comprising said upper and lower sections or to position to form an open space between the notched edges of the two crown sections at the front of the head.

2. A hat comprising a lower crown section, 100

an upper crown section having a depending approximately circular wall telescoping around the upper end of the lower crown section, and means pivotally connecting said two crown sections and permitting movement of the upper crown section to position to telescope about the entire upper end of the lower crown section to form a closed crown comprising said upper and lower sections and permitting movement of said upper crown section to a tilted position to form an opening at the front of the crown of the hat between said two crown sections, as desired.

3. A hat comprising a lower crown section, an upper crown section having a depending approximately circular wall telescoping around the upper end of the lower crown section, means pivotally connecting said two crown sections and permitting movement of the upper crown section to position to telescope about the entire upper end of the lower crown section to form a closed crown comprising said upper and lower sections and permitting movement of said upper crown section to a tilted position to form an opening at the front of the crown of the hat between said two crown sections, as desired, and means forming passages for air through the sides of the upper crown section.

EDWARD WITTCOFF.
